UNITED STATES PATENT OFFICE.

JOHN S. MONAGHAN, OF ROCHESTER, NEW YORK, ASSIGNOR TO GERMAN-AMERICAN
BUTTON COMPANY, OF ROCHESTER, NEW YORK, A CORPORATION OF NEW YORK.

DESIGN FOR A BUTTON.

50,843.

Specification for Design.

Patented May 29, 1917.

Application filed March 23, 1917. Serial No. 157,030. Term of patent 3½ years.

To all whom it may concern:

Be it known that I, JOHN S. MONAGHAN, a citizen of the United States, and a resident of Rochester, Monroe county, State of New York, have invented a new, original, and ornamental Design for Buttons, of which the following is a specification.

My design is represented in the accompanying drawing, in which:

Figure 1 is a plan view of a button showing my new design.

Fig. 2 is a side elevation of the same.

Fig. 3 is a section on line 3—3 of Fig. 1.

The button is cylindrical in form and the top surface is provided with a ridge around its periphery, and in the center is a substantially rectangular projection, flat on top and provided with outwardly extending beveled

edges, as shown. Between the center projection and the outer edge are four depressions the boundaries of which form ridges 90° apart. The inner wall of the outer edge gradually slopes inwardly to meet the bottom of the depressions.

I claim—

The ornamental design for a button substantially as shown and described.

In witness whereof I have hereunto set my hand at Rochester, in the county of Monroe and State of New York this 15th day of March, 1917.

JOHN S. MONAGHAN.

In presence of—

ERNEST BROWN,
GERTRUDE M. HILLER.
